[57] CLAIM

The ornamental design for an electrical connector, as
shown and described herein.

DESCRIPTION

FIG. 1 is a front and upper right perspective view of an
electrical connector showing my new design with the
retaining element separated for clarity;FIG. 2 is a front elevation view of the electrical connector
with the retaining element assembled;

FIG. 3 is a rear elevation view thereof;

FIG. 4 is a right side elevation view thereof with the
opposite side being identical; and,FIG. 5 is a top plan view thereof with the opposite side
being identical.The broken line showing is included for the purpose of
illustrating environmental elements only and forms no
part of the claim design.FIG. 1

FIG. 3

FIG. 2

FIG. 4

FIG. 5
